BY S. W. Bates

ATTY.

UNITED STATES PATENT OFFICE.

WILLIAM L. GILBERT, OF AUBURN, MAINE.

LOOM ATTACHMENT.

Application filed September 15, 1924. Serial No. 737,693.

To all whom it may concern:

Be it known that I, WILLIAM L. GILBERT, a citizen of the United States, residing at Auburn, in the county of Androscoggin and State of Maine, have invented certain new and useful improvements in Loom Attachments, of which the following is a specification.

My invention relates to looms and particularly to an attachment to be applied to looms for the prevention of knots, snarls and bunches of various sorts which are liable to form in connection with the warp threads when the loom is running.

Such obstructions sometimes cause the warp threads to break and under some circumstances result in the failure of the drop-wires of the loom stop motion to drop and stop the loom, so that the loom instead of stopping, continues to run without notice to the weaver that bad cloth is being produced.

For the purpose of keeping the warp free from knots and obstructions of this sort I make use of a so called flattened lease rod which extends between the warp threads, the lease rod being subjected to a rocking or twisting motion actuated by one of the moving parts of the loom and which tends to continually separate the warp threads and allow them to approach each other.

As herein shown the lease rod is mounted at each end on a spring pressed and longitudinally movable support so that when the warp threads become tangled and are not separated by the rocking motion of the lease rod, the support is made to slide longitudinally of the threads by contacting with the lease rod.

Means are provided so that the lease rod when moved a certain limited distance, by such an obstruction, connects with the mechanism for stopping the loom.

The snarls and tangles referred to which are liable to happen particularly in cotton looms which result in the abnormal conditions found in the working of the loom and which my invention is designed to correct, are as follows, and are given in the order of their frequency.

1. Certain defects of the warp are caused by so called, "hard sizing" which is the improper mixing of the starch or sizing in the slasher.

This causes a bunch on the yarn which

will not pass through the opening in the drop-wires.

If these yarns become snarled around the drop-wire the obstructions are liable to collect so that the drop-wires will not drop to 60 stop the loom.

In such cases the drop-wires are liable to stay up and the loom will be kept running continuously making bad cloth and sometimes necessitating the removal of the warp 65 beam and the redrawing of the warp.

2. The crossing of the warp threads. Where the warp threads cross and get snarled together they often cause breaks which are detected by the drop-wires which 70 stop the operation of the loom.

3. A further cause of trouble is the knots which are frequently made in the warp threads by the spinners and weavers.

In passing through the slasher these knot-75 ted threads become loaded down with starch, the flying ends become tangled with the warp threads sometimes causing the breaking of the threads and sometimes causing larger snarls which prevent the wire from 80 dropping and stopping the loom.

4. A still further difficulty is found in the fibers which are always floating about a cotton mill and which cause bunches to collect on the warp threads.

These bunches as they pass through the slasher are flattened out and sometimes cause large snarls among the drop-wires where they fail to pass through the openings.

The result may be the holding up of the 90 drop-wires from dropping and stopping the loom.

All of the troubles that I have set forth and others not specified, are remedied by my device whereby the flattened lease rod being 95 rocked or twisted continuously is always moving the warp threads across each other and tending to clear them from any snarls or bunches. When the warp threads get stuck together and are brought in contact 100 with the lease rod the latter is moved forward horizontally and made to operate my stop motion and stop the loom.

I have illustrated my invention by means of the accompanying drawing in which:— 105

Fig. 1 is an end view of the loom,

Fig. 2 is a perspective view of my lease rod, its supports and the connecting parts.

Fig. 3 is a section on the line 3—3 of Fig. 2.

Fig. 4 is a side elevation of the chamfered 110

end of the extension of the horizontally movable rod.

Fig. 5 is a cross section through the lease rod and

5 Fig. 6 is the same with the lease rod in a more vertical position.

Fig. 1 shows a general elevation of the loom 1 in which 2 is the lathe, 3 is the lathe sword, 4—4 are the harnesses, 5 is the 10 warp, 6 is the warp beam and 7 is the arch of the loom, 8 represents the lease rod which is interposed between the strands of the warp at a point beyond their crossing point and which extends the entire width of the 15 cloth. Each end of the lease rod is supported by a support 9 having an opening 10 therethrough, through which passes the end of the lease rod.

The lease rod is so constructed and 20 mounted that when the loom is in operation it will be subjected to a tilting or rocking motion. As herein shown, a vertical rod 13 extends through each end of the lease rod, the upper end of the rod 13 having 25 an adjusting screw engaging the screw thread 12, the lower end of the rod 13 being provided with an eye 14 which engages an eye 15 on one end of a horizontal rod 16. On the other end of the rod 16 30 is an eye 16' by which the rod 16 is pivoted to a bracket secured to the lathe 2.

Thus the vibration of the lathe exerts a longitudinal motion of the rod 16 and thence through the vertical rod 13 a rocking motion 35 is imparted to the lease rod 8.

The effect of the rocking motion of the flat lease rod 8 is to continue to separate 40 the warp threads and to allow them to return to their first position forming a cross motion which tends continually to remove 45 knots and snarls which may be formed in the warp.

The usual warp stop motion is applied 50 to the loom by means of a series of drop-wires 40 which are strung along the bar 50.

Each of the warp threads 5 is made to 55 pass through a hole in one of the drop-wires 40 so that when a warp thread breaks the drop-wire will be allowed to fall.

50 When one of the wires 40 is allowed to drop by reason of the fact that it is not supported by the warp thread 5 or any of them, it falls to the position shown in dotted lines in Fig. 2. When in this position it 55 enters the path of the vibrating feeler rod 30 and is held by being interposed between the feeler bar 30 and the fixed bar 31 and the loom is thereupon stopped.

There are certain contingencies in the 60 operation of the loom where hardened starch and similar materials collect around the drop-wires and prevent them from falling and stopping the loom. When such contingencies happen the loom is liable to continue to run without notice to the weaver

that there is any trouble and as a result much bad cloth is woven which is many times quite impossible to mend.

I provide that when obstructions come 70 against the lease rod by the snarling of the yarn, by masses of sizing mixed with the yarn or by other obstructions becoming mixed with the warp yarns the lease rod will slide longitudinally to a limited extent and thereby operate a very sensitive 75 mechanism by which the loom will be stopped.

For the purpose of operating the stop motion I extend forward from the supports 80 9 a rod 22 which extends forward passing through an upright 21 formed on one of the lugs on the horizontal rails 20.

For the purpose of giving a slight spring tension I coil a light spring 23 about the 85 rod 22.

Means are provided by which the loom is stopped when the supports 9 are moved horizontally a limited distance. For this purpose I provide on the end of the rod 22 an extension 41' formed on the side of 90 the collar 41 which is adjustably secured by a set screw 42 at the end of the rod 22.

The extension 40' is formed of a flattened bar having a narrow face 43 chamfered off in such a way that when it slides forward 95 beneath the arm 60 it will lift the same and consequently depress the arm 63 on the opposite side of the hub 64 to which both arms are secured. The hub 64 is pivoted on a spindle 62 which passes through the 100 hubs 64 and 65 substantially parallel with the rod 22.

The hub 65 is formed on the end of the bracket 66 the latter being secured to the 105 loom 1 by a nut 67 which passes through it. The stop arm 63 on the opposite side of the hub from the arm 60 is normally held at an inclination so that it is out of the path of the vibrating feeler bar 30.

When the extension 40' is moved longitudinally by the rod 22 it lifts the arm 60 and depresses the arm 63 as shown by dotted lines in Fig. 2. The arm 63 is when depressed, in the path of the vibrating feeler bar 30. The arm 63 is thus held 110 between the feeler bar 30 and the fixed bar 31 and the loom is stopped.

For the purpose of keeping a light tension between the bar 60 and the chamfered surface 43 a light spring 61 is interposed 115 between the end of the bar 60 and the bracket 66.

It will be seen that the rocking action of the lease rod 8 while the loom continues to run has the effect of rubbing the warp threads 5 with a cross motion against each other and this cross motion effects the clearing of the warp threads in many cases and allows the loom to weave the cloth free 125 from imperfections.

As already stated there are occasions when the warp threads are badly snarled, loaded with starch sizing and other like obstructions accumulate on the drop-wires so that 5 the latter refuse to drop and the loom continues to run.

By combining a stop motion herein shown, with a continually rocking flat lease rod I have found that the snarls and obstructions 10 are worked out as the rocking lease rod moves horizontally in contact with the warp.

As a matter of fact I find that the combined action of the flat lease rod always rocking and in the state of agitation combined with the stop motion operated by the 15 horizontal motion of the lease rod has the effect on most looms of straightening out most of the bad weaving and enables the loom to run continuously and make good cloth substantially all the time. 20

I claim:—

1. In a loom, the combination of a rocking lease rod formed to create a cross motion between the opposing threads, supports for 25 the ends of said lease rod, means for allowing said supports to move horizontally, a chamfered element rod moved horizontally by the motion of said support, a horizontal rod substantially parallel with said chamfered element rod, a sleeve on said horizontal rod, a projecting arm on said sleeve contacting with said chamfered element rod to

twist said sleeve and a stopping arm on said sleeve adapted to enter the path of the stop motion vibrating rod thereby to stop the 35 loom.

2. In a loom, the combination of a rocking lease rod, a support therefor, a movable rod connected with said support and slidable longitudinally of the warp, a chamfered extension bar for adjustably connecting with 40 said movable rod, a fixed rod substantially parallel with said extension, and movable rod, a sleeve adapted to contact with the chamfered portion of said extension, a stop 45 arm projecting from said sleeve normally out of the path of the vibrating feeler bar and adapted to be brought into said path by the longitudinal motion of said extension to stop the loom. 50

3. In a loom the combination of a rocking lease rod, a support therefor, a movable rod connected with said support and slidable longitudinally of the warp, a chamfered extension bar for adjustably connecting 55 with said movable rod, a fixed rod substantially parallel with said extension, and movable rod, a sleeve adapted to connect with said extension, a stop arm projecting from said sleeve normally out of the path of the 60 vibrating feeler bar and adapted to be brought into said path by the longitudinal motion of said extension to stop the loom.

WILLIAM L. GILBERT.
